UNITED STATES PATENT OFFICE.

NELS KROHN, OF CHICAGO, ILLINOIS, ASSIGNEE TO THE ADAMS & WESTLAKE COMPANY, OF CHICAGO, ILLINOIS, A CORPORATION OF ILLINOIS.

FAUCET.

1,125,564.

Specification of Letters Patent.

Patented Jan. 19, 1915.

Application filed January 26, 1914. Serial No. 814,477.

To all whom it may concern:

Be it known that I, NELS KROHN, a citizen of the United States, and resident of Chicago, county of Cook, and State of Illinois, have invented certain new and useful Improvements in Faucets, of which the following is a specification, and which are illustrated in the accompanying drawings, forming a part thereof.

10 The invention relates to faucets for wash-stands, especially such as are commonly used in sleeping cars.

15 The object of the invention is to provide improved means for opening the faucet by means of a plunger projecting through the table of the wash-stand, whereby the faucet may be opened with less physical effort than has heretofore been required in devices of this type.

20 The invention consists in a structure such as illustrated in the accompanying drawings, in which—

Figure 1 is a detail plan view of a wash-stand, the faucet connections being shown 25 mainly in dotted lines; and Fig. 2 is a detail vertical section through the valve casing of the faucet.

The table of the wash-stand is represented at 10, and its bowl at 11, the discharge aperture of the faucet being covered by a hood 12.

30 The water pipe is shown at 13 and rises below the wash-stand as usual, entering a valve casing 14. The valve 15 faces upwardly and closes against a seat 16 within the casing, and is held thereto by means of a spring 17 and by the pressure of the water. The valve stem 18 projects upwardly through the usual stuffing box 19.

40 The usual practice has been to have this stem extended through the table of the wash-stand, and to be provided at its upper end with a push button or plunger to which

the thumb is applied for unseating the valve. In order to open the valve it is necessary to 45 exert sufficient force to overcome not only the pressure of the spring but the pressure of the water. Frequently the environment of the washstand is such that the plunger is located below some appurtenance of the 50 car, such as a water tank, and the difficulty in opening the valve is thus increased.

In the construction as shown the valve stem 18 terminates below the top plate of the washstand, and there is provided a lever 55 20, pivoted at 21 to the lower plate 22 of the washstand table and bearing downwardly upon the valve stem. The plunger 23, to which the thumb pressure is applied, is mounted within a suitable casing 24 on the upper plate of the washstand table, and is provided with a stem 25 which extends through this plate and bears upon the free end of the lever 20. The lever is so proportioned that but slight pressure is required on the 60 plunger to depress it and open the valve. A pipe 26 leads from the upper portion of the valve casing 14 to the basin discharging under the hood 12.

I claim as my invention—

The combination of a washstand having an upper and lower plate, a water pipe, a valve casing to which the water pipe delivers and which is provided with an upwardly seating valve, a valve stem projecting through the lower plate of the washstand, a lever pivotally mounted between the upper and lower plates of the washstand, and a plunger mounted upon the upper plate of the washstand and having a stem bearing upon the free arm of the lever.

NELS KROHN.
